UNITED STATES PATENT OFFICE.

ALFRED B. REEVES, OF COLUMBUS, INDIANA, ASSIGNOR TO REEVES & CO.
AND JOSEPH I. IRWIN, OF SAME PLACE.

TRUCK FOR STRAW-STACKERS.

SPECIFICATION forming part of Letters Patent No. 279,184, dated June 12, 1883.

Application filed January 12, 1883. (No model.)

To all whom it may concern:

Be it known that I, ALFRED B. REEVES, a citizen of the United States, residing in Columbus, in the county of Bartholomew and State of 5 Indiana, have invented certain new and useful Improvements in Trucks for Straw-Stacking Machines, of which the following is a specification, having reference to the accompanying drawings.

- 10 This invention relates to an improved truck particularly adapted to be used with a straw-stacking machine of that kind which consists, essentially, of a straw-carrier mounted on a turn-table.
- 15 The object of the invention is to provide a truck which is adapted to sustain a straw-stacking machine in an elevated position during its operation in stacking straw, to allow the folding of the machine compactly on the 20 truck without separation therefrom, and which is also adapted to be easily separated from the stacking-machine after the same has been elevated in position for operation.

The accompanying drawings illustrate my 25 invention. Figure 1 is a perspective, showing the stacker in position for work, the truck forming the principal support therefor. Fig. 2 shows the truck detached and the stacker otherwise supported. Fig. 3 shows the truck 30 and stacker folded thereon for transportation. Figs. 4 and 5 are detail views, showing the means for connecting the folding uprights with the stacker-frame.

The same letters refer to the same or corresponding parts in the several figures.

A represents the turn-table on which the straw-carrier is mounted; b, the frame on which the turn-table rests.

c is a cross-bar connecting the derrick-poles 40 d d, from which the discharging end of the straw-carrier is suspended.

e is the truck-bed.

f g h i are uprights, having their lower ends pivoted to the truck-bed and their upper ends pivoted to the frame b. Uprights f and g are braced transversely by means of brace-rods j j. A brace-rod, k, which is permanently secured to the wagon-bed at one end and detachably secured to the cross-bar c at the other end, serves 50 to brace the whole longitudinally.

l is the wagon-tongue, which is adjustably secured between the hounds m n in the usual manner, so that it may be lengthened or shortened.

The upper end of each of uprights f, g, h, and 55 i is slotted to receive a short bolt, o, which projects from the inner side of frame b, as shown in Figs. 4 and 5. A bolt, p, may be passed through the upright and across the slot just above bolt o.

The operation of my device is as follows: When moving from place to place the frame b rests on the wagon-bed, the uprights folding down on the outside thereof, as shown in Fig. 3, and the straw-carrier chute is folded together, 65 and is supported on the turn-table and rear end of the truck-bed, the short upright standards r r, which are formed in the bed, serving to keep the chute from shifting sidewise. Upon arriving at the place for building the stack the 70 derrick is erected, and the frame b and its superincumbent mechanism is raised, the wagon being at the same time drawn toward the thrasher and the end of the tongue connected with the rear end of the thrasher. Brace-rod 75 k is now connected with cross-bar c. Short bars s s, attached to the frame b, at the same time enter sockets provided for them on the under side of bar c, and serve to hold the derrick closely against the frame.

When the stacker is to remain for some time in one position, it is desirable that the wagon be removed, so that the straw, which always falls to some extent from the hopper of the straw-carrier chute, may be easily removed. In 85 such case that end of the frame b which is farthest from the derrick is supported by suitable legs attached thereto, and the bolt p in each of the uprights f g h i having been removed, the wagon-tongue is disconnected from the thrasher, the wagon is backed, and the uprights slip off from the bolts o, as clearly shown in Fig. 2, the front end of the frame b being supported by the derrick in the manner fully described in another application which I have 95 made for a patent for improvement in stackers.

I claim as my invention—

1. The combination, with the base-frame, the turning straw-carrier, and a carrying-truck, of 100 uprights pivoted to said truck and detachably

connected with the base-frame, and adapted, also, to fold down upon the truck while so connected, and means for bracing said uprights in a vertical position, all substantially as shown and described.

2. The combination, with a truck-bed and a frame forming the base of a turning straw-carrier, and provided at each corner with a projecting bolt, *o*, of uprights *f*, *g*, *h*, and *i*, hav-

ing their lower ends pivoted to the truck-bed and their upper ends slotted, as shown and described, and means for bracing said uprights in a vertical position, substantially as shown and described, for the purpose specified.

ALFRED B. REEVES.
